UNITED STATES PATENT OFFICE.

CARL H. HEIDE, OF SEATTLE, WASHINGTON, ASSIGNOR TO PERFECLITE MANUFACTURING COMPANY, OF SEATTLE, WASHINGTON, A CORPORATION OF WASHINGTON.

DESIGN FOR A SUSPENDED LIGHT-FIXTURE.

• 58,567.

Specification for Design.

Patented Aug. 2, 1921.

Application filed October 20, 1920. Serial No. 418,334. Term of patent 7 years.

To all whom it may concern:

Be it known that I, CARL H. HEIDE, a citizen of the United States, residing at Seattle, in the county of King, State of Washington, have invented a new, original, and ornamental Design for a Suspended Light-Fixture, of which the following is a specification, reference being had to the accompanying drawing, forming part thereof.

The figure is a perspective view of a suspended light fixture.

I claim:

The ornamental design for a suspended light fixture as shown.

CARL H. HEIDE.
